UNITED STATES PATENT OFFICE

153,826

DESIGN FOR A COFFEE MAKER OR SIMILAR ARTICLE

Giordano Robbiati, Milan, Italy, assignor to Oscar Colcaire, Detroit, Mich., and Arthur R. Wilson, Washington, D. C.

Application June 26, 1947, Serial No. 139,948
In Italy September 14, 1946

Term of patent 14 years

(Cl. D44—26)

To all whom it may concern:

Be it known that I, Giordano Robbiati, a citizen of Italy, residing at Milan, Italy, have invented a new, original, and ornamental Design for a Coffee Maker or similar article, of which the following is a specification, reference being had to the accompanying drawing, forming a part thereof, wherein:

Fig. 1 is a front elevational view of the coffee maker or similar article, showing my new design;

Fig. 2 is a side elevational view thereof with a receptacle for the coffee in place;

Fig. 3 is a rear elevational view thereof; and

Fig. 4 is a plan view thereof.

I claim:

The ornamental design for a coffee maker or similar article as shown.

GIORDANO ROBBIATI.
